FANCIFUL MOUSE FIGURINE

Mary K. Doyle, 202 James Road,
Glen Burnie, Md. 21061

Filed Nov. 24, 1971, Ser. No. 202,065

Term of patent 3½ years

Int. Cl. D21—01

U.S. Cl. D34—2 R

FIG. 2

FIG. 1

FIG. 3

FIG. 1 is a front elevational view of the fanciful mouse figurine embodying my new design;

FIG. 2 is a right side elevational view thereof;

FIG. 3 is a rear elevational view thereof; and

FIG. 4 is a plan view thereof.

I claim:

The ornamental design for a fanciful mouse figurine, as shown.
